TRACK CLEANING CAR

Jerry J. Broz, 1202 Vine St., Scranton, Pa. 18510

Filed Mar. 3, 1971, Ser. No. 120,796

Term of patent 14 years

Int. Cl. D21—01

U.S. Cl. D34—15

Fig.1

Fig.3

Fig.2

Fig.4

Fig.5

FIG. 1 is a right side elevational view of a track cleaning car, showing my new design.

FIG. 2 is a left side elevational view thereof.

FIG. 3 is a top plan view thereof.

FIG. 4 is a rear elevational view thereof, and

FIG. 5 is a front elevational view thereof.

The bottom is without ornamentation.

I claim:

The ornamental design for a track cleaning car, as shown and described.
